UNITED STATES PATENT OFFICE.

WILLIAM H. BAKER, OF NEWTON, KANSAS.

MECHANICAL CALENDAR.

Application filed March 31, 1924. Serial No. 703,293.

To all whom it may concern:

Be it known that I, WILLIAM H. BAKER, a citizen of the United States, residing at Newton, in the county of Harvey and State 5 of Kansas, have invented certain new and useful Improvements in Mechanical Calendars; and I do declare the following to be a full, clear, and exact description of the invention, such as will enable others skilled 10 in the art to which it appertains to make and use the same.

My invention aims to provide a rather simple, yet a very desirable calendar which may be quickly and easily adjusted for use 15 in any month in a number of years.

In carrying out the above end; a pair of rotatable disks are mounted between a face plate and a back plate, and another object 20 is to provide novel means for easily adjusting these disks.

With the foregoing in view, the invention resides in the novel subject matter herein-after described and claimed, the description being supplemented by the accompanying 25 drawings.

Figure 1 is a front elevation.

Figure 2 is a vertical sectional view on line 2—2 of Fig. 1.

Figure 3 is a horizontal section on line 30 3—3 of Fig. 1.

Figure 4 is a horizontal sectional view on line 4—4 of Fig. 1.

Figures 5 and 6 are elevations of the two 35 rotatable disks.

Figures 7 and 8 are detail sections as indicated by lines 7—7 and 8—8 of Fig. 1.

In the drawings above briefly described, the numeral 1 designates a suitable face plate having a relatively large opening 2, with the 40 names of the seven week days along the upper edge of such opening. At another suitable point, the face plate 1 is formed with a smaller opening 3, and the plate may well be turned inwardly as indicated at 4, at 45 opposite edges of this opening.

Behind the face plate 1, is a movable exhibitor 5, which is preferably in the form of a rotatable disk. This exhibitor is divided, for instance, by the lines 6, into four 50 zones 7, 8, 9 and 10, all displaying month day numbers. The zone 7 is devoted entirely to thirty day months; zone 8 is devoted to thirty-one day months; zone 9 to the month of February when the latter has twenty-eight days; and zone 10 to February 55 in leap years, having twenty-nine days.

Each of the zones 7, 8, 9 and 10 displays thirteen columns of month day numbers as indicated at 11, and any seven of these columns may be displayed in the opening 60 2, in line with the week day names at the edge of this opening. The central column 11 of any of the zones, contains the numbers 1, 8, 15, 22, etc., reading from top to bottom, the numbers to the right of the central column increase consecutively from said central column, and the numbers to the left of said central column increase consecutively toward the same.

Preferably the numbers in the four zones 70 are printed in different colors or some other adequate provision is made to effectively distinguish these zones from each other. When the color scheme is used, arrows 12 may be provided near the periphery of the 75 exhibitor 5, visible through the opening 2, and the names of colors may be printed adjacent these arrows. Thus, the operator can see at a glance which direction the exhibitor must be turned to reach a zone of 80 the required color.

Also positioned behind the face plate 1 and preferably in the form of a disk disposed behind the disk 5 is another exhibitor 85 13 which is divided, for instance, by radial lines 14 into a plurality of small areas. Each of these areas, displays the name of a month, the number of a year, and the name of the first week day of said month in said year, the arrangement being such that all 90 of the months, for a number of years, are represented. The areas above referred to, designated in the drawings at 15, are intended to be selectively displayed through the opening 3, and the data contained in each area co-operates with seven of the columns 11 of a predetermined zone (7, 8, 9 or 10) on the exhibitor 5. In order to readily indicate with what zone, any particular area 15 is intended to co-act, the several 95 areas are distinguished from each other in the same manner as the several zones, one color being preferably used for all of the areas which co-operate with a zone of that color, another color being used for all of the areas cooperable with another zone, etc.

By the construction above described, the calendar may be easily set for any month in any year represented on the exhibitor 13. For instance, to set the calendar for March 110 1924, the exhibitor 13 is turned until March 1924 appears in the opening 3. At the

same time, the week day on which March 1924 started, will be displayed at said opening, as seen in Fig. 1. The color of the particular area 15 or other desired distinguishing characteristic thereof will show with which zone (7, 8, 9 or 10), said particular area is adapted to co-operate. For instance, if "March", "1924", "Saturday" appearing in the opening 3 are printed in black, the operator knows at a glance that he must adjust the exhibitor 5 until the zone printed in black, appears in the opening 2. He also knows that as the month started on Saturday, the number 1 of the zone in question must be positioned under the name "Saturday" at the edge of the opening 2. Thus, the calendar is quickly and easily set for the desired month.

In most instances, I prefer as above stated, to form the exhibitors 5 and 13 in the form of disks, and these disks are most advantageously formed of sheet metal. Sheets 16 of paper or other desired material may be secured to these disks in any suitable manner, to display the numerous legends and numbers above described, or in some instances, this data may be displayed directly on one surface of the disks.

Preferably, the two disks 5 and 13 are confined between the face plate 1 and a back plate 17, both of which may well be constructed of metal, and for lightness, I prefer to form openings 18 through all of said disks and plates. At their centers, the disks are formed with bearing openings 19 receiving a central bearing bushing 20 having reduced ends 21 received in openings 22 in the face and back plates 1 and 17. Spacing washers 23 also are preferably mounted on the bushing 20 between the disks and plates to prevent the printed matter upon the former from being obliterated by contact. The peripheral portions of the plates 1 and 17 are preferably spaced apart by sleeves 24 (see Fig. 7), screws 25 and 26 being passed through the front and back plates and threaded into said sleeves, as shown.

For turning the two disks 5 and 13, I preferably provide their edges with gear teeth 27 meshing with flat operating gears 28 of different sizes. One of these gears is disposed adjacent the front plate 1 as shown most clearly in Fig. 4, while the other is adjacent to the back plate 17, washers 29 being preferably interposed between said gears and plates, at one side of the former, while the other sides of said gears contact with peripheral enlargements 31 on a pair of operating shafts 32 which pass rotatably through openings in the plates 1 and 17 and are interposed between said gears and said plates. The shafts 32 preferably have squared portions 33 received in similar openings in the gears 28 and one end

or the other of said shafts may also be squared as indicated at 34, to engage suitable operating knobs 35.

By the construction just described, the calendar may be easily assembled and the parts 70 arranged for easily rotating the disks 5 and 13, whether the knobs 35 are at the front or the rear side of the device.

If desired, the face plate 1 may carry a clock dial 36 and the shafts for operating 75 the clock hands, may pass through the central bushing 20. When this is done, a clock mechanism is of course suitably connected with the plate 17, and a suitable glass cover (not shown) will preferably extend over the entire front of the device to protect the same. Similarly, when the calendar is manufactured for use independently of a clock, it may be mounted if desired in a suitable frame having a glass 80 front.

As excellent results are obtainable from the details disclosed, they are preferably followed, but within the scope of the invention as claimed, numerous changes may be 90 made.

I claim:

1. A calendar comprising a face plate having a relatively large opening and week 95 day names along an edge thereof, said face plate also having a relatively small opening; a movable exhibitor behind the face plate having four zones, one of said zones being devoted to thirty day months, the second zone being devoted to thirty-one day months, the third to the month of February with twenty-eight days, and the fourth to February with twenty-nine days; each of said zones having thirteen columns of month 100 day numbers, any seven columns of which may be viewed simultaneously through said relatively large opening in line with said week day names, the central column of said month day numbers containing the numbers 105 1, 8, 15, 22, etc., reading from top to bottom, the numbers of the columns at the right of said central column increasing consecutively from the above specified numbers while the numbers of the columns at 110 the left of said central column increase 115 consecutively toward said specified numbers; and a second exhibitor having small areas adapted to be selectively displayed through the small face plate opening, each of said areas displaying the name of a month, the number of a year, and the name of the first week day of said month in said year, provision being made for identifying any of said areas with the proper one of the above-named zones with which it is to co-act. 120

2. A calendar comprising a face plate having a relatively large substantially segmental opening and week day names along one curved edge thereof, said face plate having also a relatively small opening 125

spaced from the center of the face plate a distance greater than said relatively large opening, a comparatively small exhibiting disk behind said face plate divided circumferentially into four zones devoted respectively to thirty day months, thirty-one day months, February with twenty-eight days and February with twenty-nine days; each of said zones having thirteen radial columns of month day numbers, the numbers of any zone being printed in a different color from those of the other zones, any seven of the aforesaid columns of numbers being adapted to be viewed simultaneously through said relatively large opening of the face plate in line with said week day names, the central column of said month day numbers containing the numbers 1, 8, 15, 22, etc., reading from the center of the disk toward the peripheral edge thereof, the numbers at one side of said central column increasing con-

secutively from the above specified numbers, while the numbers at the columns at the other side of said central column increase consecutively toward said specified numbers; and a relatively large exhibiting disk behind the first named disk and mounted co-axially therewith, the portion of the large disk which projects beyond the smaller disk being radially divided into small areas adapted to be selectively displayed through the small face plate opening, each of said areas displaying the name of a month, the number of a year, and the name of the first week day of said month in said year, the printing displayed by any of said areas being in the same color as the printing of one of the aforesaid zones with which said area is adapted to co-act.

In testimony whereof I have hereunto affixed my signature.

WILLIAM H. BAKER.
